UNITED STATES PATENT OFFICE

GEORG OGURKOWSKI, OF ZUG, SWITZERLAND, ASSIGNOR TO LANDIS & GYR, A.-G., A JOINT-STOCK COMPANY OF SWITZERLAND

TIME SWITCH

Application filed September 11, 1929, Serial No. 391,779, and in Switzerland September 11, 1928.

The invention relates to new and useful improvements in time switches of the type wherein the actuations of the switches are automatically progressively varied; as from day to day in corresponding to the day light curve of a particular locality.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction arrangements, combinations and improvements herein shown and described.

The accompanying drawing, referred to herein and constituting a part hereof, illustrate one embodiment of the invention, and together with the description, serve to explain the principles of the invention.

Of the drawing:

Fig. 1 is a front elevation of a mechanism embodying the invention;

Fig. 2 is a vertical section taken substantially on line 2—2 of Fig. 1; and

Fig. 3 is a detached detail view of part of the mechanism shown in the other figures.

The invention is directed to improvements in time switches, and like switching and circuit-controlling apparatus, wherein astronomical day discs or dials are employed having scales graduated in hours of the day and in months, and it is directed more particularly to providing such switches and like apparatus which are of simple construction, having few parts, and at the same time are accurate and reliable in operation, and are provided with time compensations for variations in latitude and longitude of different places, and especially providing such compensations for variations in or differences between local time and standard time.

Where previous mechanisms of the general type described have been employed in different latitudes and longitudes, and the switching operations have to be effected in accordance with the particular local time, it has been necessary either to provide a

larger set of the cam or eccentric discs or wheels effecting the astronomical movement, or special cams or eccentric discs or wheels must be made for the particular place where the switching apparatus is to be set up, in accordance with the daylight curve of such particular place.

In the first instance above, since both the degrees of latitude and longitude must be taken into consideration, a double set of these cams or eccentric wheels is required. This necessitates complicated storekeeping for these accessory parts. In the latter instance above, the manufacture of such switching apparatus in large quantities is very troublesome, since the great variation in parts required precludes automatic production by means of jigs, templates, and other like appliances.

By the present invention an astronomical day disc or dial time switch mechanism is provided, which obviates the objections set forth, and which permits the manufacture automatically in quantity of all the parts of such mechanism, the apparatus at the same time being adapted to permit the switching to take place in accordance with the local time for the place of operation. Furthermore, the mechanism may be operated or serviced by a relatively unskilled attendant.

Referring now in detail to the embodiment of the invention illustrated by way of example in the accompanying drawing, the time switch mechanism is shown mounted in suitable relation upon, or in operative relation to a clock or other time measuring device. As so embodied, a stud or supporting rod 2 is fixed to and projects from the frame 3 of the clock mechanism, and the time switch mechanism is rotatably mounted on rod 2.

The diurnally rotatable mechanism comprises a sleeve 4, rotatably mounted on the supporting rod 2, which sleeve carries the time switching mechanism. Fixed to sleeve 4 is a pinion 5, which is driven from the clock mechanism, as by a pinion 1, to impart timed rotation to the switching device, and normally rotates the sleeve 4 once in twenty-four hours. Fixed also on sleeve 4 to rotate therewith is a disc 6, which carries the switch ac-

tuating devices, together with the mechanism which operates automatically to variably regulate or control the time of actuation thereof. The disc 6 abuts on a flange 7 formed on sleeve 4 and is thus maintained in position upon the rotating sleeve 4.

The switch actuating devices mounted on disc 6 to rotate therewith comprise two arms or levers 10 and 11, one being the "morning" lever and the other the "evening" lever, and operating respectively, to open and close the light circuit or circuits. On arm 10 is mounted a switch engaging pin 12 and a switch engaging pin 13 is mounted on arm 11. The switch engaging pins are preferably mounted on their respective arms by means of screw and slot mountings 15, carried by a plate 16, mounted within the flanged end of the lever arm 10 or 11, respectively.

The switch actuating arms 10 and 11 are mounted to rotate diurnally with the clock-driven disc 6, and at the same time to have the necessary capacity for angular or astronomical positioning or regulation. As embodied, said levers are loosely mounted on a hub 20, fixed to disc 6 on sleeve 4, and each arm has a finger 21, bent about the periphery of disc 6, and thus serving as a guide for the arm. For the purpose of permitting movement of said actuating arms angularly, in the astronomical regulation in connection with the diurnal rotation, a curved lever 23 for each lever arm 10 and 11 is pivoted at 24 on disc 6. Each lever arm 23 has a forked end 25 which engages with a pin 26, fixed to and projecting from the corresponding switch actuating lever 10 or 11, through an opening 27 in disc 6. Each lever 23 is provided with a pin 28 which bears on the corresponding positioning cam of the astronomically compensating mechanism, and the lever mechanism is resiliently held to its cam by a spring 29.

The astronomical regulating mechanism comprises two cams 30 and 31, fixed on a sleeve 32, which is loosely mounted on the sleeve 4. The cams are angularly positionable as desired and are fixed in such desired position. They are held in spaced-apart position by a flange 33 formed on the sleeve. Fixed also on sleeve 32 is a pinion 34, which meshes with gear mechanism for effecting the requisite astronomical relative movement or rotation of the cam discs 30 and 31 relatively to the diurnally rotating disc 6. Said gear mechanism is not shown in detail, but various forms thereof are known and any known or other suitable form thereof may be employed. A pointer 36 is preferably mounted on rod 2 and carries the change wheels, or similar mechanism for effecting the astronomical turning or compensation described.

In the embodied form of dial mechanism and the compensatingly positionable mountings therefor, a plurality of pillars 40, pref-

erably four in number, are fixed to and project from the outer face of the diurnally rotating disc 6, and each of these posts is provided with a concentric screw-threaded aperture. Screws 41 are screw-threaded into the posts 40, and an annular dial 43 carrying the hours of the day indications is mounted upon said screws by means of slots 44, whereby the dial has angular movement relatively to the diurnally rotatable disc 6, and may be fixed in any desired angular position. Concentrically mounted within the hour of the day or time-indicating disc 43, and resting in a recessed portion thereof, is the annular month-indicating dial 46. This dial has screw holes through which the screws 41 pass, and thereby the month-indicating dial is in fixed angular position, or driving relation, with reference to the disc 6 and rotates therewith. This mounting permits the time-indicating scale 43 to be angularly variably positioned with respect to the month-indicating scale and the diurnally rotating disc 6. For the purpose of effecting an exact relative positioning, or time-compensation, of the two dials there is provided on the month-indicating disc 46 an auxiliary time indicating scale 47, which is divided into time-indications and is shown as indicating one hour either way from a central point. This auxiliary time scale cooperates with an initial mark 48 or 48', located a semi-circumference apart upon the time-indicating dial.

This auxiliary scale 47 corresponds to the astronomical divisions of the world, in the sense that the time-indicating dial 41 may be compensatingly positioned forwardly or backwardly relatively to the month-indicating dial 46, in the present instance to the extent of one hour either way. By this means, a switch set up at any definite place and provided with the mechanism indicated can take up its work of switching according to the local time obtaining at such place, the clock itself being set according to the standard time obtaining in the territory including the place in question. The wide range of compensating positioning provided enables the device to meet the requirements of practically any locality, i. e., to enable the time-indicating dial to be compensatingly positioned exactly in accordance with the operation of the apparatus, even when the meridian of the place at which the apparatus is installed has an extreme position relatively to the meridian determining the standard time obtaining in the territory including the locus of the apparatus.

The invention, notwithstanding that the time-indicating scale of the dial corresponds with standard time, permits the switching operations to take place according to the local time, and any one not familiar with the construction and operation of the mechanism can directly adjust the day disc or time-indi-

cating dial, which has been once adjusted suitably for the place where it is installed, according to the standard time obtaining in the territory or locus, and which is, of course, generally known.

5 The time compensating means provided by the present invention renders it unnecessary to take into consideration the cams or eccentric discs in respect to the degree of 10 longitude, which effects great simplification in the storekeeping in respect to such dials or discs.

15 The supports 40 for the dials are so disposed or relatively spaced that the month-indicating dial 46 can be mounted only in the position shown or in a position 180 degrees therefrom. This enables the dials to be used for both the northern and southern hemispheres, as in the northern hemisphere the 20 scale 47 would cooperate with the indicator 48 and in the southern hemisphere with the indicator 48'. Likewise in the southern hemisphere the cam discs 30 and 31 would have to be interchanged.

25 The invention in its broader aspects is not limited to the details of the specific embodiment illustratively disclosed and described, but changes may be made therein within the scope of the accompanying claims without departing from the principles of the invention 30 or sacrificing its chief advantages.

What I claim is:—

1. A time switch control mechanism including in combination a member to be rotated in accordance with time, a month indicating scale thereon, an hour indicating scale supported thereby and movable relative thereto, a scale to indicate relative displacement of the hour scale from its normal position and indicating the corrections made for local time, switch operating members movable relative to the hour scale, means for moving said members relative thereto in accordance with seasonal changes in the setting 40 and rising of the sun.

45 2. A time switch control mechanism including in combination a member to be rotated in accordance with time, a month indicating scale thereon, an hour indicating scale supported thereby and movable relative thereto, a scale to indicate relative displacement of the hour scale from its normal position and indicating the corrections made for local time, switch operating members movable relative to the hour scale, means for displacing said members from their normal position to cause the switching operation to be displaced a predetermined amount of time 50 from normal.

55 60 In testimony whereof, I have signed my name to this specification.

GEORG OGURKOWSKI.
